US00D622278S

(12) **United States Design Patent**
Ma

(10) **Patent No.:** **US D622,278 S**
(45) **Date of Patent:** **** Aug. 24, 2010**

(54) **FLASH DRIVE**

TW M368821 11/2009

(75) Inventor: **Tien-Chi Ma**, Taipei (TW)

(73) Assignee: **PNY Technologies, Inc.**, Parsippany, NJ (US)

(**) Term: **14 Years**

(21) Appl. No.: **29/311,791**

(22) Filed: **Jun. 24, 2009**

(51) **LOC (9) Cl.** **14-02**

(52) **U.S. Cl.** **D14/480.6**

(58) **Field of Classification Search** **D14/356, D14/411, 433, 435.1, 436, 137, 155, 167, D14/168, 203.1–203.8, 240, 242, 299, 480.1–480.7, D14/484.1; D3/201, 273; D13/107, 108, D13/149, 184; 710/300, 301; 439/131, 135–147; 361/679.31, 679.33, 679.4, 752; 711/100, 711/115**
